US0D1056260S

(12) **United States Design Patent** (10) **Patent No.:** **US D1,056,260 S**
(45) **Date of Patent:** **** Dec. 31, 2024**

(54) **LIGHT**

(71) Applicant: **RBW STUDIO, LLC**, Kingston, NY (US)

(72) Inventors: **Theodore Richardson**, Kingston, NY (US); **Charles Brill**, Rhinebeck, NY (US); **Alexander Williams**, New Paltz, NY (US); **Gray Davis**, New York, NY (US); **William Meyer**, New York, NY (US)

(73) Assignee: **RBW STUDIO, LLC**, Kingston, NY (US)

(**) Term: **15 Years**

(21) Appl. No.: **29/936,035**

(22) Filed: **Apr. 5, 2024**

Related U.S. Application Data

(63) Continuation of application No. 29/916,231, filed on Nov. 9, 2023, which is a continuation of application (Continued)

(57) **CLAIM**

The ornamental design for a light as shown and described.

DESCRIPTION

FIG. 1 is a perspective view of a light showing our new design;

FIG. 2 is another perspective view thereof;

FIG. 3 is a front elevational view thereof;

FIG. 4 is a rear elevational view thereof;

FIG. 5 is a left side elevational view thereof, the right, top, and bottom side views being identical thereof;

FIG. 6 is a perspective view of a second embodiment thereof;

FIG. 7 is another perspective view thereof;

FIG. 8 is a front elevational view thereof;

FIG. 9 is a rear elevational view thereof; and,

FIG. 10 is a left side elevational view thereof, the right, top, and bottom side views being identical thereof.

The broken lines depict portions of the light that form no part of the claimed design.

1 Claim, 10 Drawing Sheets
